UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 14,447, dated November 27, 1883.

Application filed September 26, 1883. Term of patent 3½ years.

To all whom it may concern:

Be it known that I, CATHERINE O'HARA, of the city, county, and State of New York, have invented and produced a new and original Design for a Pattern of a Lady's Costume, (numbered 8,907;) and I do hereby declare that the engraved prints accompanying this specification convey to any one accustomed to using paper patterns a clear understanding of how a garment made up by the pattern will appear.

The design shows a round walking-skirt and a polonaise, which latter descends nearly to the bottom of the skirt, and has closely-fitted fronts that flare below the closing, a closely-fitted back showing an under-folded box-plait at the

lower end of the center seam, and a scarf-drapery showing a shirring at the end of the closing and loose folds, tacked below the side back seams, its ends falling to the bottom of the polonaise. Coat-sleeves, a standing collar, and a deep shawl-collar are added.

What I claim as my invention, and desire to secure by Letters Patent, is—

The design for a lady's costume, as shown in the engraved prints accompanying this specification.

CATHERINE O'HARA.
